T. L. TALIAFERRO

PROCESS OF CLOSING JARS

Filed March 28, 1921

FIG. 1.

FIG. 2.

Inventor

Thomas L. Leon Taliaferro

By

Stewart Mason

Attorney

UNITED STATES PATENT OFFICE.

THOMAS LUCIEN TALIAFERRO, OF CHICAGO, ILLINOIS.

PROCESS OF CLOSING JARS.

Application filed March 28, 1921. Serial No. 456,304.

The invention relates to new and useful improvements in the process of closing receptacles, and more particularly closing jars.

An object of the invention is to provide 5 a process of closing jars, whereby the closure may be secured to the jar and the jar sealed by the reforming of the plastic sealing material.

In the drawings which show by way of 10 illustration one embodiment of the invention—

Figure 1 is a vertical sectional view through a jar having a closure thereon shaped so that the sealing material may be 15 reformed in accordance with my process for securing the closure to the jar;

Figure 2 shows the sealing material as 20 having been operated upon for closing the jar.

25 In carrying out the process, I prefer to use a closure consisting of a top portion 1 having an inverted channel portion 2 adapted to receive the extreme upper edge of the wall of the jar, which is indicated at 3.

25 Said channel portion extends into an outwardly projecting portion 4 which fits close to the outer wall of the jar throughout a portion of its length and is then tapered outwardly and downwardly, as indicated 30 at 5. Formed as a part of this portion 5 is an outwardly projecting portion 6, which is provided with a depending flange 7. A pocket is thus formed between the inner wall of the depending flange 7, the 35 lower wall of the outwardly projecting portion 6, the inner wall of the tapered portion 5 and the outer wall of the jar, which pocket may be said to terminate in a horizontal line containing the lower edge of the flange 7.

40 Located in this pocket and projecting therefrom is a sealing ring 8 which is preferably formed of rubber which has not been vulcanized to any great extent, so that this sealing material is very plastic and is 45 capable of being reformed and maintaining its new shape. Said ring not only projects from the pocket, but is of slightly greater area than the cross sectional area of the pocket down to a horizontal line 50 containing the lower edge of the flange 7.

This closure per se forms no part of the present invention, but is shown, described and claimed in my co-pending application,

Serial Number 456,303, filed of even date herewith.

55

The closure, as above described, is placed on the jar, a ring of sealing material adapted to be reshaped and retain its new shape is placed in the pocket, as described above, after which the closure is pressed firmly on 60 the jar and while held pressed on the jar, a suitable instrument, such as a ring member 9, made preferably in sections, is brought underneath the sealing material and is forced upwardly into engagement 65 with the sealing material. This crowds the sealing material up into the pocket, filling the tapered portion of the pocket, formed by the outwardly projecting portion 5 of the closure, causing the sealing material to 70 firmly grip and adhere to the side walls of the pocket and the side walls of the jar. This crowding of the sealing material into the pocket brings about a very tight seal and serves as an efficient means for retaining the closure on the jar. It will be noted that by my process of closing, I bring about 75 a seal without in anyway bending the metal of the closure. Heretofore, in the closing of jars, as far as I am aware, there has 80 been a reshaping or bending of the metal and this, of course, brings more or less pressure to bear upon the glass forming the jar, often resulting in breaking the jar.

85 By my improved process, I am able to seal the jar without any bending of the metal and the only pressure against the jar is through the plastic sealing material itself, which, of course, is more or less elastic, and thus the breakage is reduced to a minimum. It is obvious that the jar may be shaped in various ways and the steps of the process may be greatly varied. The essential feature consists in the reshaping or remolding of the sealing material after the 90 closure is placed on the jar for bringing about the seal.

95 Having thus described my invention, what I claim as new and desire to secure by Letters Patent, is:

100

The process of sealing a jar having a straight outer face comprising placing a closure on the jar, which closure has a depending flange spaced from the side wall of the jar so as to form a pocket therebetween, placing a ring of sealing material 105

capable of being re-formed and retaining its re-formed shape in said pocket, said ring being of greater cross-sectional area than the pocket and protruding from the pocket, exerting a pressure on the protruding portion of the sealing ring while holding the closure on the jar so that said sealing ring is forced into the pocket and wedged

between the depending flange of the closure and the side wall of the jar, whereby the closure is sealed on the jar and held on the jar by the sealing material.

In testimony whereof, I affix my signature.

THOMAS LUCIEN TALIAFERRO.
